UNITED STATES PATENT OFFICE.

CLIFFORD E. WENTZEL, OF DAYTON, OHIO, ASSIGNOR TO INTERNATIONAL CLAY MACHINERY COMPANY, OF DAYTON, OHIO, A CORPORATION OF MAINE.

FURNACE GAS PRODUCER.

Application filed April 22, 1920. Serial No. 375,714.

To all whom it may concern:

Be it known that I, CLIFFORD E. WENTZEL, a citizen of the United States, residing at Dayton, in the county of Montgomery and State of Ohio, have invented certain new and useful Improvements in Furnace Gas Producers, of which the following is a specification, reference being had therein to the accompanying drawing.

10 This invention relates to furnace gas producers and the like.

In gas producers of the type with which the present invention is employed, the combustion chamber of the furnace is separated 15 from the ash pit by a structure which is adapted to support the fuel and ashes in the combustion chamber, and which is movable to discharge the ashes therefrom into the ash pit. Arranged above the supporting structure are one or more tuyères through which a mixture of air and steam is forced into the fuel to cause the combustion necessary to the 20 production of the gas. As heretofore constructed, the tuyères have been mounted on and secured to the supporting structure which was hinged to permit it to be tilted to cause the ashes to be discharged therefrom. This construction was open to various objections. It was heavy and difficult to 25 operate and also expensive to manufacture. In dumping the ashes a portion of the same will enter the tuyères and the conduit leading thereto and if these are not removed more or less frequently they will choke up the 30 pasageway to such an extent as to prevent the passage of the steam and air through the tuyères. Further, when the supporting structure is tilted to dump the ashes all support for the bed of fuel in the combustion 35 chamber is removed and there is danger, particularly with a free burning fuel, of dumping the fire into the ash pit. This, of course, would put the furnace out of operation until a new fire could be built and where 40 the furnace is connected with a kiln, the ware which was being fired would be seriously damaged and probably ruined.

One of the objects of the present invention is to provide, in a device of this kind, a 50 supporting structure which will be of light weight and easily operated.

A further object of the invention is to pro-

vide such a device having means for supporting the bed of fuel when the supporting structure is moved to dump the ashes, 55 thus preventing the possibility of the fuel being dumped into the ash pit.

A further object of the invention is to provide such a device in which any ashes which may have entered the tuyères will be 60 automatically discharged therefrom when the supporting structure is moved into dumping position.

Other objects of the invention will appear as the mechanism is described in detail.

In the accompanying drawings Fig. 1 is a front elevation of a furnace gas producer embodying my invention; Fig. 2 is a transverse sectional view taken through the supporting structure and tuyères; Fig. 3 is a 70 longitudinal sectional view taken on the line 3—3 of Fig. 1; and Fig. 4 is a sectional view taken horizontally through the furnace showing the supporting structure and tuyères in plan.

In these drawings I have illustrated one embodiment of my invention and have shown the same in connection with a furnace gas producer of a known construction, but it will be understood that the present 80 embodiment has been chosen for the purpose of illustration only and that the invention may take various forms and may be applied to furnaces of various kinds.

In the construction here illustrated, the 85 furnace comprises a combustion chamber 1 and an ash pit 2. Interposed between the ash pit and the combustion chamber and adapted to support the fuel and ashes in the combustion chamber is a structure 3 90 which is so arranged that it will normally close the pasageway between the combustion chamber and the ash pit. The opening, or pasageway, which is closed by this supporting structure may be formed in any 95 suitable manner, as by a proper arrangement of the masonry, or by a supplemental structure carried by the masonry. In the present instance I have employed a bed plate 4 which is supported at its edges on the masonry at the top of the ash pit, the masonry being provided with suitable ledges to form supports therefor. This bed plate is provided with an opening 5 of large area

beneath the central portion of the combustion chamber, and the supporting structure 3, when in position in this opening, will support the bulk of the ashes and fuel in 5 the combustion chamber. The supporting structure is movable into and out of its position in the opening in the bed plate so that the ashes which have accumulated thereon may be dumped from time to time. Preferably 10 the structure is hinged to the bed plate so that it can have a swinging movement into a tilted, or dumping, position, which will cause the ashes to be discharged therefrom. As here shown, the bed plate 15 and supporting structure are provided at adjacent edges with lugs 6 and 7 adapted to receive a hinge pin, or shaft, 8. To facilitate the return of the supporting structure to its normal, or closed, position the lugs 7 thereof are rigidly secured to the hinge pin, or shaft, 8 and the latter projects to the outer end of the furnace where it may be engaged by a suitable instrument for 20 rotating the same and thus raising the supporting structure. As here shown, the end of the shaft is squared to receive a long handled wrench or like instrument. This supporting structure may be retained in its closed position by any suitable means but 25 I prefer to arrange a locking device at the free edge of the structure and, as here shown, a locking rod 9 is journaled in bearing lugs 10 rigidly secured to and extending beneath the bed plate 4 and is provided between 30 said bearings with an offset portion 11 adapted to be moved beneath the edge of the supporting structure. The locking rod extends to the outer end of the furnace and is provided with a handle 12 by means of which it may be actuated. The supporting structure is provided with a stop to 35 limit the inward movement of the offset portion of the locking rod, and this stop is so arranged that when said locking rod is in engagement therewith the offset portion thereof will lie slightly beyond a vertical plane extending through the axis of its rotation, thus causing the thrust exerted upon the rod by the supporting structure to tend 40 to move the rod inwardly and thereby preventing it from being forced outwardly and releasing the structure. The supporting structure 3 is here shown as a metal plate, which, for the sake of lightness, is comparatively thin and is reinforced by a plurality of transverse and longitudinal ribs 13 and 14, and one of the ribs 14 constitutes the stop for the locking rod.

Arranged above the supporting structure 45 are one or more tuyères 15 which may be of any suitable number and construction. In the present instance, I have employed two tuyères, which extend lengthwise of the furnace and are preferably supported independently of the supporting structure

3. In the present construction the tuyères are supported on the bed plate 4 at the front and rear ends of the opening 5 and are removable. In order to properly position the tuyères with relation to the opening 5 and retain them in their proper positions I have provided each tuyère at its rear end with a longitudinally extending lug 16 having therein a slot 17 to embrace a stud 18 rigidly secured to and extending upwardly from the bed plate 4. Preferably the slot is flared to facilitate its engagement with the stud and the stud is provided with a head to engage the lug and hold the tuyère against movement, other than an outward longitudinal movement. The tuyères at their forward ends rest upon the bed plate and are provided with longitudinal tubular extensions 19 constituting nozzles into which a jet of steam is discharged. The arrangement of the nozzles and the manner of discharging the steam into the tuyères may take various forms, but in the present construction I have formed the nozzles 19 for the two tuyères independent one 90 of the other and have provided a steam jet 20 for each nozzle, these steam jets being carried by a pipe 21 which can be swung outwardly to permit the removal of the tuyères. The nozzles, or tubular extensions, 95 19 may be connected with the tuyères and may be supported upon the bed plate in any suitable manner but, in the present construction, I have shown them as formed integral with the tuyères and as disconnected from and resting upon the bed plate 4, the latter being provided with a seat 22 to support the same in their proper positions. Each tuyère 15 is provided with openings 100 to discharge into the mass of ashes and fuel resting upon the supporting structure and, in the present instance, these openings are formed along the lower edges of the lateral walls thereof, as shown at 23, and if desired the side walls of the tuyères may be provided with depending portions 24 which rest upon the supporting structure 3 to support the intermediate portions of the tuyères and which divide the openings 23 into a plurality of parts. The tuyères are provided in their bottoms with openings which are normally closed by the supporting structure 3, when the latter is in its closed position, and preferably the tuyères are bottomless.

It will be apparent from the foregoing description that when it is desired to remove the ashes from the combustion chamber the supporting structure is moved out of the opening 5 in the bed plate 4, thus permitting the ashes to drop into the ash pit. This movement of the supporting structure also opens the bottoms of the tuyères and permits any ashes which may have entered the same through the openings 23, to be dis-

charged therefrom. Thus the tuyères are cleaned each time the ashes are dumped and there is no possibility of their being clogged with ashes. Further, the tuyères are supported independently of the supporting structure 3 and do not move therewith, consequently, there is much less tendency for the ashes to enter the tuyères. The tuyères remain in their normal positions above the 10 opening 5 in the bed plate and constitute grate bars which serve to support the fuel when the structure 3 has been moved into its dumping position and thereby prevent the bed of fuel from dropping into the ash pit 15 along with the ashes. It will also be apparent that the mechanism is very simple in its construction and consequently inexpensive to manufacture, and further, that the supporting structure 3 is of light weight and can be 20 easily restored to its normal position after the ashes have been dumped.

While I have shown and described one embodiment of my invention I wish it to be understood that I do not desire to be limited 25 to the details thereof as various modifications may occur to a person skilled in the art.

Having now fully described my invention what I claim as new and desire to secure by 30 Letters Patent, is:

1. The combination with a furnace comprising a combustion chamber and an ash pit, of a structure interposed between said combustion chamber and said ash pit to support fuel and ashes in said combustion chamber, said structure being movable to permit the ashes thereon to be dumped from the combustion chamber into the ash pit, a tuyère arranged above and extending across 35 said structure and having openings leading into the ashes and fuel on said structure, a nozzle arranged in line with said tuyère, and a steam jet discharging into said nozzle.

2. The combination with a furnace comprising a combustion chamber and an ash pit, of a structure interposed between said combustion chamber and said ash pit to support fuel and ashes in said combustion chamber, said structure being movable to permit the ashes thereon to be dumped from the combustion chamber into the ash pit, and a tuyère arranged above and extending across 50 said movable structure and supported independently thereof.

3. The combination with a furnace comprising a combustion chamber and an ash pit connected one to the other by a passageway, of a structure arranged to close said passageway and to support fuel and ashes in said 55 combustion chamber, said structure being movable to permit the ashes thereon to be dumped from the combustion chamber into said ash pit, and tuyères extending across said passageway above said movable structure and supported independently of said

structure to constitute fuel supporting means when said movable structure has been moved to its dumping position.

4. The combination with a furnace comprising a combustion chamber and an ash pit, of a structure interposed between said combustion chamber and said ash pit to support fuel and ashes in said combustion chamber, said structure being movable to permit the ashes thereon to be dumped from the 70 combustion chamber into the ash pit, and a tuyère arranged above and extending across said structure, supported independently thereof, and having an opening in the bottom thereof adapted to be closed by said 75 movable structure when the latter is in its normal position.

5. The combination with a furnace comprising a combustion chamber and an ash pit, of a structure interposed between said 80 combustion chamber and said ash pit to support fuel and ashes in said combustion chamber, said structure being movable to permit the ashes thereon to be dumped from the combustion chamber into the ash pit, a 85 tuyère arranged above and extending across said movable structure and having a tubular extension projecting therefrom, and a steam jet arranged to discharge into said tubular extension.

6. The combination with a furnace comprising a combustion chamber and an ash pit, of a structure interposed between said combustion chamber and said ash pit to support fuel and ashes in said combustion chamber, said structure being movable to permit the ashes thereon to be dumped from the combustion chamber into the ash pit, a tuyère arranged above said structure and supported independently thereof, said tuyère being provided with laterally extending 100 openings and having parts intermediate its length to engage said supporting structure when the latter is in its normal position.

7. The combination with a furnace comprising a combustion chamber and an ash pit, of a bed plate interposed between said ash pit and said combustion chamber and having an opening therein, a structure movable into and out of a position to close said 105 opening and adapted to support fuel and ashes in said combustion chamber, and a tuyère supported by said bed plate, extending across said opening and having outlets arranged to discharge into the fuel and ashes on said movable structure.

8. The combination with a furnace comprising a combustion chamber and an ash pit, of a bed plate interposed between said ash pit and said combustion chamber and having an opening therein, a structure movable into and out of a position to close said 115 opening and adapted to support fuel and ashes in said combustion chamber, and a tuyère supported by said bed plate and ex- 120

tending across said opening, said tuyère having an opening in the bottom thereof arranged to be closed by said movable structure when the latter is in its closed position.

5 9. In a device of the character described, a structure normally arranged to support fuel and ashes and movable out of its supporting position to cause the ashes to be discharged therefrom, and a tuyère arranged above and 10 extending across said structure and supported independently thereof.

10 10. In a device of the character described, a structure normally arranged to support fuel and ashes, said structure being hinged 15 at one edge thereof to permit it to be moved from its supporting position to cause the ashes thereon to be dumped, and a tuyère arranged above and adjacent to the normal position of said supporting structure, extending 20 across the same and supported independently thereof.

11. In a device of the character described, a structure arranged normally to support fuel and ashes, said structure being hinged 25 at one edge thereof to permit it to be moved from its supporting position to cause the ashes thereon to be dumped, and a tuyère arranged above and adjacent to the normal position of said supporting structure, extending 30 across the same and supported independently thereof, said structure having an opening in the bottom thereof arranged to be closed by said supporting structure when the latter is in its normal position.

35 12. In a device of the character described, a bed plate having an opening therein, a closure for said opening adapted to support fuel and ashes and mounted for movement away from said opening to permit the ashes to be dumped, and a tuyère supported on said bed plate above said opening.

13. In a device of the character described, a bed plate having an opening therein, a closure for said opening adapted to support fuel and ashes and mounted for movement away from said opening to permit the ashes to be dumped, and a tuyère supported on said bed plate above said opening, said tuyère having an opening in the bottom thereof arranged to be closed by said closure when the latter is in its closed position.

50 14. In a device of the character described, a bed plate having an opening therefor, a closure hinged at one edge to said bed plate and adapted to support fuel and ashes, means for retaining said closure normally in its supporting position, and a tuyère mounted on said bed plate and extending across said opening.

60 15. In a device of the character described, a bed plate having an opening therein, a closure for said opening hinged along one edge to said bed plate and adapted, when in its closed position, to support fuel and 65 ashes, a locking rod extending along the

other edge of said closure and having an offset portion adapted to engage said closure to retain the same in its closed position, and a tuyère supported by said bed plate above said opening.

70 16. In a device of the character described, a bed plate having an opening therein, a movable closure for said opening adapted to support fuel and ashes, a tuyère arranged above and extending across said supporting structure, a nozzle for said tuyère supported by said bed plate and arranged in alinement with said tuyère, and a steam jet discharging into said nozzle.

75 17. In a device of the character described, a structure adapted to support fuel and ashes and movable into a position to cause the ashes thereon to be discharged therefrom, a tuyère supported above and extending across said movable structure, a nozzle supported independently of said movable structure and arranged in line with said tuyère, and a steam jet discharging into said nozzle.

80 18. In a device of the character described, a bed plate having an opening therein, a closure for said opening hinged at one edge to said bed plate and adapted to support fuel and ashes when in its closed position, a plurality of tuyères supported on said bed plate and extending across the opening therein and adapted to constitute grate bars when said closure is moved to its open position, and means for discharging air and steam into said tuyères.

85 19. In a device of the character described, a bed plate having an opening therein, a closure for said opening hinged at one edge of said bed plate and adapted to support fuel and ashes when in its closed position, a plurality of tuyères supported by said bed plate, extending across said opening, and adapted to form grate bars when said closure is in its open position, each of said tuyères having an opening in the bottom thereof arranged to be closed by said closure when the latter is in its closed position, and means for discharging steam and air into said tuyères.

90 20. The combination with a furnace comprising a combustion chamber and an ash pit, of a bed plate interposed between said ash pit and said combustion chamber and having an opening therein, a structure movable into and out of a position to close said opening and adapted, when in its closed position, to support fuel and ashes, a tuyère extending across said opening, and means for removably supporting said tuyère on said bed plate.

95 21. The combination with a furnace comprising a combustion chamber and an ash pit, of a bed plate interposed between said ash pit and said combustion chamber and having an opening therein, a structure movable into and out of a position to close said

opening and adapted, when in its closed position, to support fuel and ashes, a tuyère extending across said opening, said tuyère and said bed plate having interlocking parts 5 in the rear of said opening and said bed plate having a seat in front of said opening to receive said tuyère.

22. The combination with a furnace comprising a combustion chamber and an ash pit and having an opening in the front wall thereof leading to said combustion chamber, of a bed plate interposed between said ash pit and said combustion chamber and having an opening therein, a structure movable 15 into and out of a position to close said opening and adapted, when in its closed position, to support fuel and ashes, a tuyère removably supported by said bed plate and extending across said opening, said tuyère 20 having a slotted portion at its inner end and said bed plate having a stud to enter said slotted portion, said tuyère having a tubular extension at the forward end thereof, and said bed plate having a seat to receive 25 said tubular extension.

23. The combination with a furnace comprising a combustion chamber and an ash pit, of a bed plate interposed between said ash pit and said combustion chamber and 30 having an opening therein, a tuyère extending across said opening, said tuyère and said bed plate having interlocking parts in the rear of said opening and said bed plate having a seat in front of said opening to receive 35 said tuyère.

24. The combination with a furnace comprising a combustion chamber and an ash pit, of a structure interposed between said combustion chamber and said ash pit to support fuel and ashes in said combustion chamber, said structure being movable to permit the ashes thereon to be dumped into the ash pit, a tuyère arranged above and extending across said structure and having 40 openings leading into the ashes and fuel on said structure, a nozzle communicating with said tuyère, and a steam jet discharging into said nozzle, said movable structure and said

tuyère being so arranged with relation one to the other that the movement of said structure into dumping position will cause the ashes which have accumulated in said tuyère to be discharged therefrom. 50

25. In combination with a furnace comprising a combustion chamber and an ash pit, of a device interposed between said combustion chamber and said ash pit to support fuel and ashes in said combustion chamber, the supporting surface of said structure having a movable portion, a tuyère arranged 55 above said movable portion having openings leading into the ashes and fuel of said supporting device, said tuyère being so mounted with relation to said movable portion that when the latter is moved from its closed 60 position it will move away from said tuyère, and means for delivering steam to said tuyère.

26. In combination with a furnace comprising a combustion chamber and ash pit, 70 of a device interposed between said combustion chamber and said ash pit to support fuel and ashes in said combustion chamber, the supporting surface of said structure comprising a hinged portion, a tuyère arranged 75 above said hinged portion and having openings leading into the ashes and fuel above said supporting device, said tuyère being so mounted with relation to said hinged portion that when the latter is moved about its 80 axis it will move away from said tuyère, and means for delivering steam to said tuyère.

27. In combination with a furnace comprising a combustion chamber and an ash pit, 85 a structure interposed between said combustion chamber and said ash pit to support fuel and ashes in said combustion chamber, the supporting surface of said structure comprising a movable portion, and a tuyère 90 arranged above said movable portion of said structure, said movable portion being capable of movement relative to said tuyère.

In testimony whereof, I affix my signature hereto.

CLIFFORD E. WENTZEL.
